UNITED STATES PATENT OFFICE.

ADOLPH SAMETZ, OF NEW YORK, N. Y.

DESIGN FOR A RING-HOLDER.

SPECIFICATION forming part of Design No. 24,320, dated May 21, 1895.

Application filed March 22, 1895. Serial No. 542,857. Term of patent 7 years.

To all whom it may concern:

Be it known that I, ADOLPH SAMETZ, a citizen of the United States, residing at New York city, in the county and State of New York, have invented and produced a new and original Design for a Ring-Holder, of which the following is a specification, reference being had to the accompanying drawings, forming a part thereof.

- 10 In the drawings, Figure 1 is a plan view of a ring-holder, showing my design; and Fig. 2 is a perspective view showing one corner of the holder, these two views being deemed necessary to fully illustrate my design.
- 15 The leading feature of the design consists in the series of elongated U-shaped tongue-like figures A, appearing on the rectangular board B, said figures A appearing in regular order and being rounded and enlarged at 20 their upper ends and contracted at their central portions, below which points the said

figures are formed at opposite sides with projecting portions, the lower sides of which are inclined inward toward each other to the bases of the figures A, as clearly seen in Fig. 25 1. At opposite sides of the base of each of the figures A on the rectangular figure B, a small circular figure D appears, and about midway between each of said figures D a circular ornamental figure F appears. The edges 30 of the rectangular figure B display a lace-work ornamentation G, and under the figure B an ornamental surface H appears through the figures D and F of the figure B.

I claim—

35 The design for a ring holder, herein shown and described.

ADOLPH SAMETZ.
